UNITED STATES PATENT OFFICE.

GEORGE W. HINKLE, OF MENDON, MICHIGAN.

CHECK-HOOK FOR HARNESS.

SPECIFICATION forming part of Letters Patent No. 227,435, dated May 11, 1880.

Application filed March 25, 1880. (No model.)

To all whom it may concern:

Be it known that I, GEORGE W. HINKLE, of Mendon, in the county of St. Joseph and State of Michigan, have invented certain new and 5 useful Improvements in Check-Hooks for Harness; and I do hereby declare the following to be a full, clear, and exact description of the invention, such as will enable others skilled in the art to which it pertains to make and 10 use it, reference being had to the accompanying drawings, which form part of this specification.

My invention relates to an improvement in check-hooks for harness; and it consists in placing inside of one end of the hook a piece 15 of rubber, which may be attached either to the end of the hook itself or placed in a recess in the top of the screw-bolt which unites the hook to the saddle, and which rubber has 20 a pin or stud projecting outward from it, and which stud is formed to play back and forth so as to let the check-rein be drawn out of the hook, and yet will prevent the check from becoming accidentally detached, as will be more 25 fully described hereinafter.

The object of my invention is to provide a cheap and simple means for preventing the check-rein coming loose from the hook, as it is very apt to do when the horse throws back 30 his head, and thus prevent the annoyance of having to get out of the vehicle and readjust it.

Figure 1 represents a vertical section of one form of my invention. Fig. 2 is a cross-section of the same, taken at right angles to Fig. 3. Fig. 3 shows another form of my invention.

A represents a check-hook, of the usual form, and which is to be attached to the saddle B 40 in any suitable manner. Made in the head of the bolt C, which passes down through the saddle and the hook, is a suitable recess, D, and in this recess is placed a block of rubber, E. This rubber fits the recess so tightly that 45 there is no possibility of its becoming displaced while the bolt is in position. Embodied in this piece of rubber, and projecting upward through the slot in the top of the bolt, is a pin

or projection, I, which is free to play back and forth in a line with the slot through the head of 50 the bolt. This pin, as the check is being introduced into the hook, will bend forward toward the horse's head, so as to let the rein pass over it; but as soon as it is left free to move it snaps back into position again, and serves as a stop 55 to prevent the check-rein from becoming accidentally loosened.

Instead of placing this piece of rubber in a recess in the top of the bolt, as above described, a suitable rubber band, L, having a 60 projection, I, embedded in it, may be placed upon the upper end of the hook, as shown in Fig. 3. As the projection I cannot be pulled out of the rubber, owing to its head, and as the rubber allows the projection to play back 65 and forth in any direction, the rein can be pulled into the hook past the projection, and the projection will not allow it to be displaced.

Whether this projection is held in the bottom of the hook, as shown in Figs. 1 and 2, or attached to the hook, it forms a very simple and effective stop for preventing the check-rein from becoming loosened from any cause, and thus saves the necessity of the driver having 70 to get out of the vehicle to fasten it.

Having thus described my invention, I claim—

1. In combination with a check-hook for harness, a base or block of rubber and a pin 80 or projection extending therefrom, so as to form a stop to prevent the check-rein from becoming unhooked, substantially as shown.

2. The combination of a check-hook with a bolt passing down through it and the saddle, 85 and having a recess in its top to receive a block of rubber, and a slot through its upper end for the pin or projection I to play back and forth in, substantially as set forth.

In testimony that I claim the foregoing I 90 have hereunto set my hand this 23d day of March, 1880.

GEORGE W. HINKLE.
